THERMOSTATIC LOCK FOR THE CLOSURES
OF COMBUSTION APPARATUS OR THE
LIKE

Theodore B. Focke, Cleveland Heights, and Evans W. Cheeseman, Cleveland, Ohio, assignors to Perfection Stove Company, Cleveland, Ohio, a corporation of Ohio

Application January 17, 1939, Serial No. 251,392

1 Claim. (Cl. 220—40)

This invention is an automatic lock, of a thermosensitive or thermostatic character, for use with enclosures that are subjected, alternately, to relatively low and high temperatures and are provided with openings through which access may be had to their interiors, said openings being equipped with closures; and it is the broad purpose of the invention to provide means for preventing said closures from being opened when a relatively high temperature prevails within the enclosures.

The invention was conceived in connection with liquid fuel burning apparatus of the kind in which the fuel is fed to a burner bowl or firepot wherein it is vaporized and receives primary air thereby to produce a relatively rich mixture. This mixture, in an initial state of combustion, rises and, being rendered more highly combustible by the addition of secondary air, burns with practically complete combustion in a combustion space or chamber above. The bowl or pot is provided with a relatively large lighting and clean-out opening normally closed by suitable means, desirably in the form of a plug. If this closure or plug is removed when the apparatus is in operation and, as a consequence an abnormally high quantity of air is suddenly admitted to the bowl or pot, it causes an explosion resulting in a gush of fire outwardly through the lighting and clean-out opening endangering person and property.

It is a more specific object of the invention, therefore, to provide a thermostatic lock for the plugs or closures of the lighting and clean-out openings of combustion apparatus of the above described type; and although the invention is herein disclosed in this particular association, obviously it is of broader application and is susceptible to all ramifications coming within the scope of the claim appended hereto.

Other more general objects are the attainment of simplicity, reliability, durability and cheapness in locking means of the kind referred to.

Additional objects and advantages will appear in the course of the following description wherein reference is made to the accompanying drawings in which Fig. 1 is a fragmentary central vertical section through a liquid fuel burning apparatus incorporating the invention; Fig. 2 is a front elevation of the sleeve that surrounds the lighting and clean-out opening with the closure or plug positioned therein; Fig. 3 is a section on the line 3—3 of Fig. 1, looking in the direction indicated by the arrows; Fig. 4 is a longitudinal

section through one side of the sleeve and plug showing the position the plug occupies with respect to the sleeve when the plug is fully entered but before it is turned to secure it in place, the 5 thermostatic lock being in the position it occupies when the parts are relatively cool; and Fig. 5 is a view similar to Fig. 4, showing the thermostatic lock in the effective position it assumes under the influence of a relatively high temperature and with the plug withdrawn as far as permitted by the lock.

The structure shown fragmentarily in Fig. 1 is that of a furnace incorporating liquid fuel combustion apparatus of the kind hereinbefore referred to. The burner bowl or firepot is designated 1 and includes an annular top wall 2, the central opening of which is surrounded by a depending lip 3. Connected to and spaced above the top wall 2 by means of a number of shouldered rivets or the like, one of which is shown at 4 in Fig. 1, is an assembly comprising an annulus 5 flanged downwardly about its inner edge to form a lip 6 that is spaced inwardly from and is substantially concentric with the lip 3; a top wall 7 of a housing later to be described, and a ring-like member 8, the outer rim portion of which is connected, as by fastening means or bolts 9, to the annular bottom wall 10 of a combustion chamber 11.

15 The top wall 7 constitutes a part of a housing, designated generally by the numeral 14, which includes a peripheral wall 15 and a bottom wall 16, the latter having a central opening 17 for admitting air to an air chamber designated 20 that is enclosed by said housing and surrounds the burner bowl or firepot 1. The top wall 7 of said housing has a central opening registering with the openings of the annulus 5 and the ring-like member 8, said openings providing communication between the burner bowl or firepot and the combustion chamber 11. From the chamber 20, primary air enters the bowl or pot 1 through holes 25 in the peripheral wall thereof, and secondary air enters over the top wall of the bowl

40 or pot and through the annular slot between the lips 3 and 6, the lips serving to deflect the secondary air downwardly. Liquid fuel is supplied to the sump-like bottom of the bowl or pot through a conduit 28 that leads from a suitable source of supply (not shown). Pursuant to usual practice, a liquid level control is included in the connections between the source and bowl or pot.

45 The peripheral wall of the bowl or pot 1 adjacent the front of the apparatus is provided with a relatively large lighting and clean-out opening

30 that is surrounded by a forwardly projecting flange 31. A tube or sleeve 32 is suitably attached to the wall of the bowl or pot about the flange 31 and in concentric relation thereto and extends forwardly a considerable distance beyond the flange 31 and through an opening in the adjacent portion of the peripheral wall 15 of the housing 14. A bell-like member 35 surrounds the part of the tube or sleeve 32 forwardly of the wall 15 and its flanged outer end joins the front wall 36 of the furnace about an opening therein.

A closure, designated generally by the reference numeral 40 and presently to be described, is provided for the lighting and clean-out opening 30.

To start the fire, the closure 40 is removed and a lighted match, taper or other igniting means is projected through the opening 30 to set fire to the fuel that has been fed to the bowl through the conduit 28. As soon as the fuel is ignited, the closure 40 is replaced so as to tightly close the opening 30 and as the bowl becomes heated the fuel is vaporized and the vapors mix with primary air admitted through the holes 25. As combustion progresses and the heat increases vapors in greater volume are produced and ultimately a slowly burning gaseous body occupies the pot or bowl 1 and as the burning mixture rises it is rendered more highly combustible by the addition of secondary air that enters between the lips 3 and 6, the large percentage of the combustion occurring above this point and within the combustion chamber.

The previously mentioned closure 40 is composed of a cylindrical plug-like body 41 to the inner end wall of which is rotatably connected or swiveled, through a pivot member 42, a gasket carrier designated generally by the reference numeral 43. This element is desirably drawn or otherwise formed from a single piece of sheet metal and comprises a circular end wall 44 and a cylindrical wall 45 whose forward end is gradually curled outwardly and then back over itself to provide an inwardly facing annular channel that contains a ring 46 of suitable non-inflammable packing material, desirably of a fibrous nature, such as asbestos. The packing ring 46 is thus sustained in a position to engage the forward end of the flange 31 when the closure 40 is inserted into the tube or sleeve 32 by means of a handle 48 attached to its forward end. The body 41 is enlarged at its forward end to nearly the internal diameter of the tube or sleeve 32 and at diametrically opposed points is provided with slots 50. The edge portions of the enlarged end of the body 41 are cut away on corresponding sides of both slots 50 to provide cam surfaces 51. Diametrically opposed abutments 55, desirably in the nature of rollers that are mounted on studs 56, are carried by and project inwardly from the tube or sleeve 30 in a position to pass through the slots 50 when the closure is inserted into the tube or sleeve. Then when the plug-like body 41 is turned

5 by means of the handle 48, the cam surfaces 51 ride over the abutments or rollers 55 thereby to force the closure inwardly and compress the packing ring 46 against the forward end of the flange 31 and seal the lighting and clean-out opening 30.

Secured, as by rivets 60, to the cylindrical wall of the plug-like body 41 near the inner end thereof and substantially in axial alignment with one 10 of the slots 50 is the inner end of a bi-metal strip 61 that constitutes the thermo-sensitive or 15 thermostatic element of the automatic locking means of our invention. Normally—that is, when the parts are cool—the outer free end of the strip 61 occupies substantially the position shown in Figs. 3 and 4 where it is disposed radially inwardly of the adjacent slot 50. When the parts become heated, the bi-metal strip assumes approximately the condition shown in Fig. 5 where its 20 outer end is in a position to engage the contiguous abutment or roller 55 when an attempt is made to remove the closure 40, thereby to prevent such removal and avoid the dangerous condition arising from the sudden admission of an abnormally large quantity of air through the lighting and clean-out opening 30, such as would produce within the burner bowl or fire pot a more highly combustible mixture than normally prevails and that would explode and flash through the opening with the liability of causing injury to the person removing the closure and possible damage to clothing or other objects.

Having thus described our invention, what we claim is:

35 In combination, a sleeve arranged with one of its ends surrounding a closure seat, a plug insertable within the sleeve and equipped at its inner end with a closure for engagement with the seat, the end of the plug remote from the closure being enlarged and slightly less in diameter than the internal diameter of the sleeve, the enlarged end of the plug having a slot that extends in a direction substantially longitudinally of the plug and a cam surface extending from one side of said slot, an abutment projecting inwardly from the sleeve in a position to pass through said slot when the plug is inserted into the sleeve and to engage said cam surface when the plug is turned, thereby to hold the plug within the sleeve and to 40 closure in engagement with the seat, and a bi-metal strip arranged alongside the portion of the plug of lesser diameter and secured to the plug at its end remote from the enlarged end of the plug, said strip being so arranged that when it is affected by a relatively high artificial temperature its free end will assume a position to block passage of said abutment through said slot and prevent removal of the plug, said strip, under atmospheric temperature, assuming a position in which it escapes said abutment.
